UNITED STATES PATENT OFFICE.

CUTHBERT COATES SMITH, OF TWICKENHAM, ENGLAND.

GRAMOPHONE APPARATUS.

Application filed August 3, 1921. Serial No. 489,590.

To all whom it may concern:

Be it known that I, CUTHBERT COATES SMITH, a subject of the King of England, and residing at Twickenham, in the county of Middlesex, England, have invented Improvements in Gramophone Apparatus (for which I have filed an application in England January 4, 1915, Patent No. 20,323, 1914), of which the following is a specification.

10 This invention relates to gramophone apparatus of the kind wherein the gramophone records are contained in a magazine which is raised or lowered by selective mechanism operated from outside the casing to 15 bring the records into proper position for removal from the magazine and from which they are removed by apparatus also operated from outside the casing and carried to and from the proper playing position under 20 the stylus of the gramophone reproducer, the brake being simultaneously removed from the gramophone revolving table.

25 My invention relates to improvements in gramophone apparatus of the indicated type and comprises a construction and arrangement of parts devised for the purpose of performing the before mentioned functions in a simplified and efficient manner; and to an improved form of carrier by which the records are positively gripped and carried to 30 and from the playing position.

35 My invention is illustrated in the accompanying drawings in connection with coin-feed mechanism, but is not restricted thereto.

35 In these drawings,

Figure 1 is a side elevation partly broken away showing the general arrangement;

40 Figure 2 is a similar view showing the magazine of records and the carrier mechanism;

45 Figure 3 is a detached elevation of the gramophone revolving table showing the reproducing apparatus and connections in the lowered or playing position, and

50 Figure 4 is a skeleton view showing the other or raised position of the same parts.

Figure 5 is a detached rear elevation showing the coin-release mechanism;

55 Figure 6 is an end elevation of same, and

Figure 7 shows the other position of the parts shown in Figure 5;

Figure 8 is a plan view showing the magazine and revolving table and connections; and

55 Figures 9 and 10 are respectively elevation

and plan of the carrier mechanism on an enlarged scale.

The same reference numerals where they occur are used to denote the same or corresponding parts in all the figures of the drawings. 60

The outer casing is provided with the usual coin aperture 1 and with two handles or hand wheels 5^b, and 18^b outside the casing and fast on the shafts 5^a, and 18^a, passing through suitable bearings in the casing and 65 carrying within the casing the disc 5 and toothed wheel 18 respectively. Each handle or hand wheel 5^b, 18^b, is provided with a pointer such as 18^c, moving over a graduated arc or other means for indicating direction of motion. 70

Within the casing (see Figures 5 to 7) is a coin shoot 1^a immediately beneath the coin aperture 1, down which the coin falls into an open bucket or frame 2 secured to a 75 counter-balanced lever 3 pivoted at 3^a. The lever 3 has pivoted thereto at 3^b, a spring catch lever 3^b, one end of which is secured by the spring 3^c to a pin on the lever 3, while the other end rests against a pin 3^d on the 80 lever 3, and extends above the upper edge of a stop 3^d secured to the casing. In the normal position of the weighted lever 3 the spring catch 3^b passes into the bucket 2 and prevents the coin falling completely 85 through. When a coin is in the bucket, the lever 3 is over-balanced and carried down slightly into the position shown in Figure 5.

To the weighted lever 3 is secured a rod 4 working in suitable guides and normally 90 engaging in a recess 5^e in the disc 5. The initial movement of the lever 3 caused by the weight of the inserted coin already described, withdraws the keeper end of the rod 4 from the disc 5 which disc can then be rotated by the handle 5^b outside the case. By this rotation a cam 5^e on the shaft 5^a is caused to engage an extension 4^a on the rod 4 which rod is thereby forced down into the 95 position shown in Figure 7. By this movement of the weighted lever 3, the spring catch 3^b is carried down against the fixed stop 3^d whereby its forward end is turned upwards against the tension of its spring 3^c, into the position shown in Figure 7, 100 clear of the open bucket 2 through which the coin is then free to fall.

On the shaft 5^a, and within the casing, is fixed a crank arm 6 (see Figures 1, 2, 4, 5 and 6) on which is a crank pin 6^a, which in 110

the normal position shown in Figure 1 presses the lower end of a lever 20 towards the rear of the casing. This lever is pivoted at 20^a to a fixed part and is connected by the link 21 with one arm of a bell crank 22 fast on a shaft 22^a extending across the machine and journalled in the frame, the other arm of this bell crank being connected by a link 22^b to an extension 17^a pivoted at 17^b to the track rail 17. The other side of the machine as shown in Figure 8 is provided with a similarly pivoted track rail extension which is connected by a link to a crank arm on the corresponding end of the shaft 22^a. On the shaft 22^a is also secured a weight or weights 22^d and an arm 22^c on the other end of which arm is connected by a telescopic link 23 with a carriage 24 (see Figure 3) having a tubular extension 24^a sliding on a vertical rod 25 fixed in the casing and provided with a stop or collar 25^a to limit the upward movement of the carriage 24. The carriage 24 is secured to a counter-weight 25^b by cords or the like flexible connections passing over pulleys secured to the casing. The tendency therefore of the weights 25^b and 22^d is to raise the track extensions 17^a to the horizontal position and to raise the carriage 24, and this result is effected when the shaft 5^a is rotated sufficiently to remove the crank pin 6^a away from the lower arm of the lever 20, whereupon these parts will pass from the dotted to the full line positions shown in Fig. 4.

Lying in the path of the pin 6^a on the crank 6 is a rod 7 having a heel piece or projection 7^a, a recess to receive the pin 6^a immediately under the heel 7^a, and a shaped lower extension 7^b which works between suitable guides. The upper end of the rod 7 is connected to one end of a bell crank 8 fast on a shaft 8^a also extending across the machine and journalled in the frame, the other arm of the bell crank being connected by a link 9 to a lever arm 10 secured to a shaft 11 also extending across the machine and journalled in the frame. The other end of the lever arm 10 is connected by a link 12 to a record carrier 13 running on the track rails 17, 17^a. Duplicate lever mechanism is connected to the shafts 8^a and 11 at the opposite side of the machine and there connected to a duplicate record carrier 13. The two positions of this record carrier mechanism are shown on Fig. 2 and the change from one to the other is effected by the rotation of the shaft 5^a through the arc there shown, the rod 7 being kept in proper position by means of the spring 7^c secured to it and to the frame.

Both record carriers are alike, but are reversely disposed to engage opposite edges of the records, and are adapted to act together and to carry the records from the

gramophone table back to the magazine at a higher level than on the reverse journey for the purpose of clearing the shelf of the magazine on to which the record is to be replaced. Both carriers are shown in plan in Figure 8, and the one on the further side of the machine is shown to an enlarged scale in elevation and plan in Figures 9 and 10. The carriers ride on the rails 17 by eyes 13^b, or by means of flanged or other wheels or other suitable means.

The carrier operating link 12 is connected to a crank lever 12^a pivoted at 12^b to the lower part of the carrier 13 and adapted to move in a guide 13^c secured to the side of the carrier. The other arm 12^c of the crank lever lies in the path of a pin 12^d on the underside of a plate 12^e which is also provided with guide pins 12^f all of which pins pass through apertures in the base of the carrier. On the top of the plate 12^e is fixed a curved arm 12^f which arm would be raised by the pin 12^d and plate 12^e when the link 12 is pressed in the direction of the arrow shown dotted in Fig. 9, as would be the case during the movement of the carrier from the revolving table 16 to the magazine 15, i. e. from the right to the left of the plan view, Figure 8, and would be lowered when it reaches the limit of such movement; it would also be lowered when moved in the opposite direction.

The curved arm 12^f is shaped to the contour of the gramophone record and grips the edge of same in conjunction with a cylindrical pin 13^b carried by an arm 13^a fixed to a sleeve on a post 13^c carried by the plate 12^e and normally held in the position shown in Figure 10 by a spring 13^d. The arm 13^a carries a curved extension 13^b provided with an antifriction roller or the like 13^e which contacts with the track rail 17 and is turned aside by fixed projections 17^d or 17^e thereby turning the arm 13^a outwards away from the centre of the machine to the position shown by the full lines in Figures 10 and 8, so as to release the grip of the pin 13^b on the edge of the record and allow same to fall on to the shelf of the magazine or on the gramophone revolving table 16, as the case may be. A stop 17^f is fixed on each track extension 17^a to limit the movement of the carriers from the magazine to the table 16, to ensure the record being deposited centrally on said table (see Figures 1, 2, and 8).

The reproducer 26 is carried down on to the record on the table 16 and the rotation of the table 16 is started by the lowering of the carriage 24, which lowering is effected by the lever mechanism already described operated by the reverse rotation of the shaft 5^a to bring the parts to the normal position shown in Figure 1.

To the carriage 24 is secured an inclined

arm 24^b (see Figure 3) which engages under the pivoted tone arm 26^a and raises and lowers same and the reproducer 26 with the carriage 24. Pivoted to a fixed part 30 5 of the machine is a bell crank lever 29, one end 29^c of which lies under the table 16 and is adapted to act as a brake to stop the rotation thereof, while the other arm is connected by a spring 31 to the frame of the 10 machine. Pivoted at 27^b to the carriage 24 is a trigger lever 27 the tail of which is held against the spring controlled crank lever 29 by a light spring 27^a secured to the carriage 24 so as to act in opposition to the spring 31 15 on the bell crank 29. The extremity of the tail of the trigger lever 27 engages between two converging electrical contacts 28 whereby the electric circuit is completed through a motor 34 (Figure 1), the motion being 20 transmitted through the pulley wheel 34^a, band 34^b, wheel 34^c, shaft 34^d, worm 34^e, work wheel 16^a to spindle 16^b of table 16. When the carriage 24 is raised the trigger 25 27 is carried upwards away from the contacts 28, breaking the electrical connection, and from the bell crank 29, the spring 31 of which latter then draws said crank over on its pivot and applies the brake 29^a to the table 16. This is in the position shown in 30 Figure 4. On lowering the carriage 24 the pointed upper end 27^c of the trigger 27 is caught by a locking catch 33^a on a lever 33 pivoted at 33^b to the carriage 24. On further lowering, the trigger 27 pushes back 35 the crank lever 29 against its spring 31 and removes the brake 29^a, and the lower end of the tail of said trigger 27 is by the spring 31 on the crank lever 29 caused to complete the circuit between the converging contacts 28.

Each record 14 is provided with an elevation or incline 32 (Figures 1, 3 and 8) over which the stylus of the producer passes from the annular space around the outer part of 45 the record grooves. This raises the tone arm 26^a, which latter raises the lever 33 thereby removing the locking catch 33^a from behind the pointed upper end 27^c of the trigger lever 27 freeing said trigger. Thereupon 50 the spring 31 pulls over the crank lever 29, breaks the electrical contact between 27 and 28 and applies the brake 29^a to the underside of the record table 16.

The records are stored in a magazine 55 secured to a rack 19^a raised and lowered by a toothed wheel 18 on the shaft 18^a, (Figures 2 and 5) said magazine being guided by tubes 15^a passing over rods 15^c fixed vertically in the casing, said magazine being 60 counter-balanced by weights 15^b attached by cords 15^a or like flexible connections passing over pulleys 15^b on the framework of the casing.

The toothed wheel 18 (see Figure 5) is 65 provided with a series of equidistant gaps

18^b, one of which is engaged by a spring locking catch 19 turning as a lever on a vertical pivot the other end of said catch riding on the rim of the disc 5. In this disc is a bevelled gap 5^a and when the shaft 5^a is 70 rotated sufficiently to bring said gap under the projecting arm of the spring catch 19 the spring on the latter causes the catch to enter the gap 5^a and to leave the gap 18^b in the wheel 18 which then is free to be rotated. 75

The sequence of operations is as follows:—

When a coin is dropped into the slot, the lever 3 is overbalanced and the rod 4 withdrawn from the disc 5. The latter may then be rotated clockwise by the hand wheel 5^b carrying the crank 6 and the pin 6^a from the position A to position C (marked in Figure 1). As the crank passes from A to B the lever 20 is released and the counter-weights 22^a and 25^b then raise the extensions 17^a of the track 17 and the carriage 24 carrying with it the gramophone reproducer away from the table 16. The arm 24^b is inclined for the purpose of returning the sound box and tone arm to the starting position on the record. As the carriage 24 is moved upwardly, the upper portion of arm 24^b engages the underside of the tone arm and lifts it off of the record at the outer edge thereof. The weight of the arm causes it to slide down the inclined arm to the outer end, in which position, the arm and sound box are located above the center of the record at the starting point of the groove therein, which runs from the center to the edge. 95 This is the position shown in Figure 4.

The movement of the crank 6 from the position B to the position C raises the rod 7 which by its lever connections 8, 9, and 10, carries the record from the table 16 to 100 the magazine 15 where it is deposited by the carriers 13 being caused, by their abutment against the front part of the casing, to lower the plates 12^a on which the record is supported, the grip pins 13^b being removed, 110 as before stated, by contact of the rollers 13^c on the arms 13^a with the fixed projections 17^d on the track.

The rotation of the crank 6 from A to C has brought the bevelled gap 5^a in the disc 5 into alignment with the spring catch 19 which thereupon snaps thereinto leaving the wheel 18 free to be rotated. This is then rotated by the operator by means of the hand wheel 18^b until the pointer 18^c points to 115 the selected record, the wheel 18 raising or lowering the magazine by means of the rack 19^a. The operator next rotates the hand wheel 5^b counter clockwise to bring the crank pin 6^a from the position C back 120 to the original position A. This reverse movement causes the spring catch 19 to leave the bevelled gap 5^a in disc 5 and enter the opposite notch in the wheel 18 locking 125 the said wheel, and the carriers 13 with the 130

- selected record gripped therein are carried back to the table 16, where the record is deposited, and the end of the movement operates the lever 20 thereby lowering the track 5 extension 17^a and the gramophone reproducer on to the record now on the table 16, simultaneously removing the brake therefrom and completing the circuit through the electric motor for driving the table.
- 10 After the stylus has passed over the whole of the record the upward projection 32 thereon raises the reproducer the tone arm 26^a of which trips the lever 33 and sets free the trigger 27 which is thereupon drawn 15 away from the electrical contacts and the brake 29^a is applied to the underside of the table 16. The parts remain in this position until the insertion of another coin when the sequence above stated can be repeated.
- 20 The telescopic connection 23 ensures that the reproducer carriage 24 shall not be lowered until after the record has been placed on the table and that the carriage shall first be raised on the reverse movement.
- 25 What is claimed is:—
1. A talking machine, including a frame, a record playing table mounted thereon, a reproducer carried by the frame, a slide member mounted on the frame for vertical sliding movement, said member having an inclined arm adapted to engage the reproducer, and means for raising and lowering the slide member, whereby when said slide member is raised the inclined arm will engage the reproducer and raise it, the incline of the arm being such that the reproducer will slide to the lower portion by gravity which will place it in the starting position.
  2. A talking machine, including a frame, a record playing table mounted thereon, a reproducer carried by the frame projecting over the record table, a slide member mounted on the frame having means for engaging the reproducer, and means for operating the slide member so that the means on said member will engage the reproducer for setting it in the starting position.
  3. A talking machine, including a frame, a record playing table mounted on the frame, a reproducer mounted on the frame extending over the record table, a motor for operating the record table, a member slidably mounted on the frame formed for engagement with the reproducer so that in the sliding movement of the member the reproducer will be placed in the starting position, and means mounted on the members cooperating with means carried by the frame for starting and stopping the motor 60 in the sliding movement of the member.
  4. A talking machine, including a frame, a record playing table mounted thereon, a reproducer mounted on the frame projecting over the record table, a member slidably mounted on the frame and formed to engage
- the reproducer for positioning it in the starting position in the sliding movement of said member, and operating means for sliding said member, comprising a hand wheel mounted on a shaft rotatable in the frame, 70 said shaft having a crank on one end thereof, and lever connections with the member adapted for operation by the crank in the rotation of the hand wheel to raise or lower said slide member. 75
5. A talking machine, including a frame, a record playing table mounted on the frame, a reproducer mounted on the frame and extending over the record table, a record magazine slidably mounted in the frame, a record carrier mounted on the frame for reciprocating movement to carry a record from the magazine to the record table and back to the magazine, and controlling means for governing the operation of the machine, 80 including a hand wheel rotatably mounted in the frame having a predetermined position during the playing of a record and having connections with the reproducer, the record carrier, and record table, whereby in 85 a partial rotation of the hand wheel, the record table will be stopped, the reproducer moved to the starting position, and the record carrier operated to carry the record from the record table and deposit it in the magazine rack, and another hand wheel rotatable in the frame for operating the magazine for selecting a desired record, the subsequent reverse rotation of the first hand wheel operating the carrier to place the desired record on the record table and start 90 the machine for playing said record. 95
6. A talking machine, including a frame, a record playing table mounted on the frame, a reproducer mounted on the frame and extending over the record table for playing a record thereon, a record magazine movably mounted on the frame to permit the selection of a desired record by the positioning thereof, a record carrier movable on 105 the frame between the magazine and the record table for conveying a selected record to the record table and back to the magazine, and controlling means for governing the operation of the machine, comprising an 110 operating crank having a predetermined position during the playing of a record and adapted for a cycle of movement after the record has been played, for operating connections with the reproducer, record table, 115 and carrier, for returning the reproducer to the starting position, moving the carrier to return the record to the magazine and stop the operation of the record table, and a record selecting means released for operation at the end of the above mentioned 120 cycle of operation of the crank for moving the magazine to select a record to be played, the operating crank having a return cycle 125 of movement to the predetermined position 130

for operating the carrier to place the record on the table, release the table and start the operation thereof to play the record.

7. A talking machine, including a frame, 5 a record playing table mounted on the frame, a reproducer mounted on the frame and extending over the record table for playing a record thereon, a record magazine movably mounted on the frame to permit 10 the selection of a desired record by the positioning thereof, a record carrier movable on the frame between the magazine and the record table for conveying a selected record to the record table and back to the magazine, 15 and controlling means for governing the operation of the machine, comprising an operating crank having a predetermined position during the playing of a record and adapted for a cycle of movement after the 20 record has been played, for operating connections with the reproducer, record table, and carrier, for returning the reproducer to the starting position, moving the carrier to return the record to the magazine and 25 stop the operation of the record table, and a record selecting means released for operation at the end of the above mentioned cycle of operation of the crank for moving the magazine to select a record to be played, 30 the operating crank having a return cycle of movement to the predetermined position for operating the carrier to place the record on the table, release the table and start the operation thereof to play the record, and 35 means for locking said operating crank against movement during the playing of a record.

8. A talking machine, including a frame, 40 a pair of parallel tracks mounted at opposite sides of the frame, a record playing table mounted on the frame between the track bars and near one end thereof, a reproducer extending over the record table and carried by the frame for playing a record on said table, a record magazine movably mounted in the frame between the tracks and near the other ends thereof, and record carriers movable from the magazine to the record table, comprising a carrier 45 member movably mounted on each rail, and gripping means on each carrier member for gripping and raising a record above the playing table and conveying it to the magazine and vice versa.

55 9. A talking machine, including a frame, a pair of parallel tracks mounted at opposite sides of the frame, a record playing table mounted on the frame between the track bars and near one end thereof, a reproducer extending over the record table and carried by the frame for playing a record on said table, a record magazine movably mounted in the frame between the tracks and near the other ends thereof, and record carriers movable from the magazine

to the record table, comprising opposed carrier members movably mounted on the tracks, vertically movable plates carried by the members for engaging the underside of a record to lift it off the record table, gripping means on the members for engaging the record to carry it from the magazine to the record table and back again in the movement of the carrier members, and means on the tracks for operating said 70 gripping means to release the record to place it in the magazine or on the table.

10. A talking machine, including a frame, a record playing table mounted on the frame, a reproducer mounted on the frame 80 and extending over the record table, a record magazine slidably mounted in the frame, a record carrier mounted on the frame for reciprocating movement to carry a record from the magazine to the record table and back to the magazine, and controlling means for governing the operation of the machine, comprising a hand wheel rotatably mounted in the frame having a predetermined position during the playing of a record and having connections with the reproducer, the record carrier, and record table, whereby the hand wheel when rotated through a cycle of movement will stop the record table, move the reproducer to the starting 90 position, and operate the record carrier to convey the record from the record table and deposit it in the magazine, a record selecting handle rotatable in the frame and connected with the magazine for operating it to select a desired record, the subsequent reverse cycle of rotation of the hand wheel operating the carrier to place the desired record on the record table and start the machine for playing said record, and means 100 normally locking the record selecting handle against movement released by the hand wheel at the end of the first mentioned cycle of rotation.

11. A talking machine, including a frame, 110 a record playing table mounted thereon, a reproducer mounted on the frame projecting over the record table, a member slidably mounted on the frame and formed to engage the reproducer for positioning it in the starting position in the sliding movement thereof, and operating means for sliding said member, comprising a bell crank lever pivotally mounted in the frame with a link connecting one arm thereof with the 115 member, a link connecting the other arm of said bell crank with a lever pivotally mounted in the frame, and a hand wheel rotatable in the frame having a crank for engagement and for operating said lever to 120 slide the member through the link connections and the bell crank.

12. A talking machine, including a frame, a record playing table mounted thereon, a reproducer mounted on the frame 125

6
projecting over the record table, a member 5
slidably mounted on the frame and formed
to engage the reproducer for positioning it
in the starting position in the sliding move-
ment thereof, a record magazine mounted
in the frame, a record carrier mounted on
the frame for reciprocating movement be-
tween the table and magazine for conveying
records from one to the other, and operating
10 means for the slide member and record car-
rier, comprising a hand wheel rotatable in
the frame having a crank for movement
therewith, a lever pivotally mounted on the
frame having one end adapted to engage
15 the crank, a bell crank lever pivotally
mounted in the frame having a link con-
necting one arm with the other end of the
first mentioned lever and another link con-
necting the other arm with the slide mem-
20 ber for operating the slide member in

the movement of the crank by the hand
wheel, and a bell crank lever pivotally
mounted in the frame having a slotted link
on one arm positioned to have the crank
engage the slot therein, a lever having one 25
end pivoted to the frame, a link connecting
the other end with the record carrier, and a
link connecting the center portion of said
lever with the other arm of the last men-
tioned bell crank for operating the record 30
carrier through the movement of the crank
by the hand wheel in engaging the slot in
said link.

In testimony whereof I have signed my
name to this specification in the presence of 35
two subscribing witnesses.
